(57) **CLAIM**

The ornamental design for a sound amplifier, as shown and described.

DESCRIPTION

1. Sound amplifier

1.1 : Perspective

1.2 : Front

1.3 : Top

1.4 : Back

1.5 : Left

1.6 : Right

1.7 : Bottom

1.8 : Perspective

The broken lines represent environmental structure and form no part of the claimed design.
